(57) **CLAIM**

The ornamental design for the fishtape, as shown and described.

DESCRIPTION

FIG. 1 is a perspective view of the fishtape.

FIG. 2 is a side view of the fishtape.

FIG. 3 is another side view of the fishtape.

FIG. 4 is a front view of the fishtape of FIG. 1.

FIG. 5 is a back view of the fishtape of FIG. 1.

FIG. 6 is a top view of the fishtape of FIG. 1; and,

FIG. 7 is a bottom view of the fishtape of FIG. 1.

The broken line showing of structural features is included for the purpose of illustrating non-claimed subject matter and forms no part of the claimed design.
